The dominant feature of the design resides in a brassiere having in combination: two back-band portions each having a top edge which is high at its front part adjacent the cup, curves down low under the arm of the wearer, and then curves up again, so that it meets a shoulder strap of the brassiere at a height considerably above its lowermost underarm height, each back-band portion having an undulating wave line of bold decorative stitching adjacent to and extending across its bottom edge, and a like undulating wave line of bold decorative stitching adjacent to and extending along its top edge from adjacent the apex of each brassiere cup in a downward arcuate path under the arm and then in an upward arcuate path to where the shoulder strap meets the back-band, all as shown in full lines.

I claim:

The ornamental design for a brassiere, as shown and described.
